Primary Examiner — Cynthia E Ramirez(74) *Attorney, Agent, or Firm* — Woodard, Emhardt, Moriarty, McNett & Henry LLP(57) **CLAIM**

The ornamental design for a plug having a tool insert opening with a non-circular constant diameter cross-section, as shown and described.

DESCRIPTION

FIG. 1 is a perspective view of the plug.

FIG. 2 is a top view of the plug; and,

FIG. 3 is a side view of the plug.

The dotted line drawing portions are for illustrative purposes only and form no part of the claimed design.
